CLAIM

The ornamental design for an electrical adapter with indicator light, as shown and described.

DESCRIPTION

FIG. 1 is a top, left front perspective view of an electrical adapter with indicator light showing Embodiment 1 of our design;

FIG. 2 is a top, right back perspective view of same electrical adapter with indicator light as in FIG. 1 embodying our design;

FIG. 3 is a top plan view thereof;

FIG. 4 is a bottom plan view thereof;

FIG. 5 is front side elevational view thereof;

FIG. 6 is a back side elevational view thereof;

FIG. 7 is a left side elevational view thereof;

FIG. 8 is a right side elevational view thereof;

FIG. 9 is a top, left front perspective view of an electrical adapter with indicator light showing Embodiment 2 of our design;

FIG. 10 is a top, right back perspective view of same electrical adapter with indicator light as in FIG. 9 embodying our design;

FIG. 11 is a top plan view thereof;

FIG. 12 is a bottom plan view thereof;

FIG. 13 is a front side elevational view thereof;

FIG. 14 is a back side elevational view thereof;

FIG. 15 is a left side elevational view thereof; and,

FIG. 16 is a right side elevational view thereof.
